CONVERTIBLE SEAT AND TABLE BASE UNIT

Martin Borenstein, Berkeley, Calif.

Application March 4, 1957, Serial No. 45,069

Term of patent 14 years

(Cl. D15—11)

Fig. 1 is a perspective view of a convertible seat and table base unit showing my new design.

Fig. 2 is a cross-sectional view thereof as taken through the portion shown in full lines and looking toward the right.

Fig. 3 is an end view as seen from the right end.

The dominant features of the design are shown in the drawing in full lines.

I claim:

The ornamental design for a convertible seat and table base unit, substantially as shown and described.
